UNITED STATES PATENT OFFICE.

ALBERT EDWARD HARRIS AND JOHN WILLIAM DRIVER, OF BRADFORD, ENGLAND,
ASSIGNORS TO THE SALT'S TEXTILE MANUFACTURING COMPANY, OF BRIDGEPORT,
CONNECTICUT, A CORPORATION OF CONNECTICUT.

BATTING-FRAME.

1,115,190.

Specification of Letters Patent. Patented Oct. 27, 1914.

Application filed April 21, 1914. Serial No. 833,354.

To all whom it may concern:

Be it known that we, ALBERT EDWARD HARRIS and JOHN WILLIAM DRIVER, both subjects of the King of Great Britain, and 5 residing in Bradford, England, have invented certain new and useful Improvements in Batting-Frames, of which the following is a specification.

In the manufacture of certain kinds of pile fabrics the goods after being dyed and washed are put through an operation known as "batting." This operation is performed while the goods are stretched tight upon a frame between boards by men standing at the sides of the goods and striking it repeatedly with a stick. When the goods are placed on the frame they are in a moist condition and the pile laid flat, the purpose of the batting being to set up vibrations in 10 the goods which have the effect of raising the pile. The operation is one requiring considerable skill and judgment upon the part of the operator and, with the usual frame as heretofore employed, the goods 15 have almost invariably shown faults which appear as narrow streaks or flat places where the pile has not been raised. These faults appear with more or less frequency, the number depending upon the skill and judgment 20 of the operator, and with greater frequency near the upper board. The subsequent removal of the faults by "doctoring" or "padding" requires considerable time, and hence adds materially to the cost of the 25 goods. Experience has shown that at least 95% of the goods require padding.

The principle of the batting operation is to set up vibrations in the goods and the faults, we believe, are due to the fact that 30 the goods are stretched on rigid and inflexible boards which act as fixed points between the two pin rolls which deaden the vibrations and prevent them extending beyond the boards, or throwing them back from the 35 top board to neutralize the vibrations caused by the beating of the sticks upon the goods. But whatever the cause, we have discovered that by giving the bearing surfaces a degree of elasticity or resiliency the 40 faults have disappeared, and that the goods batted on a frame as herein described have the pile raised uniformly over their surfaces and do not require subsequent padding.

For the purpose of explaining one embodiment of our invention we have shown the same in the accompanying drawings in which—

Figure 1 is a front elevation; Fig. 2 a vertical section on the plane of the line 2—2 of 60 Fig. 1; and Fig. 3 a detailed section through one of the batting boards.

Similar reference numerals indicate similar parts in the several views.

As shown in the drawings the batting frame comprises side members 1 connected by cross pieces 2 and suitably supported. To the frame brackets are secured upon one of which, at the lower part of the frame and at the rear thereof, the piece roll 3 is carried. The goods are run from the roll 3 over a guide roller 4 and around a pin roll 5 both supported at the lower front of the frame. Fixed on the shaft of pin roll 5 is a ratchet wheel 6 adapted to be rotated by 75 a crank 7 and held in position by a pawl 8. Immediately above pin roll 5 is the lower batting board or bearing surface over which the goods are passed to the upper batting board or bearing surface, thence to a pin 80 roll 9, mounted in brackets at the rear of the frame, and held by a ratchet and pawl 10. From pin roll 9 the goods pass through an opening 11 to the drying room. This relative arrangement of the parts is substantially that as heretofore employed, the goods being stretched tight over the bearing surfaces between the pin rolls 5 and 9 by rotating the former by means of the crank and ratchet.

Our improvement upon the prior methods of construction relates particularly to the bearing surfaces. Heretofore these have been comparatively narrow convex boards of wood rigidly secured to the side members 95 of the frame at the upper and lower parts thereof. The goods being stretched tight over these boards they presented a rigid and inflexible bearing and acted as fixed points beyond which there was no vibration 100 of the goods. We have, therefore, substituted for the non-yielding boards, resilient and flexible bearing surfaces the preferred form of which is constructed as follows. Each bearing surface consists of a piece 105 having a base 12 and a back 13 which parts may be at right angles to each other, and end pieces or walls 14 having their outer rims

formed on an arc struck from the angle of the base and back. Fitted over the opening thus formed between the base, back and end walls, is a piece or strip of rubber 15, and upon the rubber is laid a piece of canvas 16, this cover for the device being secured by screws 17 fitting openings bored into the rims of the end walls and in a flange 18 formed on the base 12, and a flange 19 5 formed on the back wall 13, as shown in Fig. 3. The devices so constructed are supported in brackets 20 secured to the side members 1 of the frame, one immediately above the pin roll 5 and the other at the upper part 10 of the frame. We thus provide a hollow device into which a fluid may be introduced to give an elastic or resilient bearing for the goods. For the purpose of inflating the boards and giving them the desired resiliency, we connect them through pipes 21 having branches 22, to a main 23 leading to a source of fluid pressure. We have used air, maintaining the pressure at from 3 to 5 pounds above atmospheric, suitable valves 24 controlling the supply. The branches 22 are connected with the bearing surfaces through openings in the back wall 13, as shown in Figs. 2 and 3. The fluid pressure is sufficient to maintain the cover in its 25 rounded or arc shape. The devices may be used as described, and as shown in Fig. 3, or upon certain classes of cloths one or more layers of felt 24' may be placed over the upper bearing surface as shown in Fig. 2.

In using a frame equipped with the bearing surfaces as above described, the goods 25 are stretched between the pin rolls as heretofore, resting upon the two intermediate resilient surfaces when subjected to the batting, the said surfaces instead of presenting a rigid and unyielding surface, present a resilient or elastic cushion to the goods, so that the vibrations of the goods are not 30 deadened at the bearing surfaces but extend beyond them, and particularly beyond the upper one. The result in practice, due to the described cushioning effect, is that the pile is caused to stand erect uniformly over the surface of the goods, and without faults. This not only adds materially to the finished 35 appearance of the goods but saves the time heretofore required for "doctoring" or "padding". Another advantage is that the resilient bearing surfaces assist to some extent the return movement of the batting stick, thereby lessening the labors of the operator.

We believe ourselves to be the first to provide a batting frame or nelly with an elastic or resilient bearing surface and particularly one with a pneumatic cushion, and we, therefore, desire to claim the same in the broadest sense. Also it is to be understood 65 that we do not desire to be restricted to

the specific means shown, as it is obvious that the invention is capable of embodiment in other forms. Instead of manual batting it will be understood that our device is equally as well adapted for any known mechanical 70 batting means.

What we claim and desire to secure by Letters Patent of the United States is:—

1. A batting frame having an elastic or resilient bearing surface thereon, and means 75 for stretching the goods over said surface.

2. A batting frame having elastic or resilient bearing surfaces at the lower and upper parts thereof, and means for stretching the goods over said surfaces.

3. A batting frame having a bearing surface with a flexible or resilient side over which the goods are stretched.

4. A batting frame having a pneumatic bearing surface secured thereto, and means 85 for stretching the goods over said surface.

5. A batting frame having a hollow device with a yielding or flexible part, means for introducing a fluid under pressure to the interior thereof, and means for stretching 90 the goods over said device in contact with the flexible part thereof.

6. A batting frame having a hollow device with a yielding or flexible part, means for introducing air under pressure to the 95 interior thereof, and means for stretching the goods over the same.

7. A batting frame having an elastic or resilient bearing surface, a felt covering therefor, and means for stretching the goods 100 taut on the frame over said covered surface.

8. A batting frame having elastic or resilient bearing surfaces at the lower and upper parts thereof, a felt covering for the upper of said surfaces, and means for stretching 105 the goods taut on the frame over said surfaces.

9. A batting frame for raising the pile of a pile fabric comprising a device having a yielding bearing surface, means for introducing a fluid under pressure to said device, means for delivering cloth to and from said device, and means for batting the pile of the cloth so delivered.

10. A batting frame for raising the pile 115 of a pile fabric comprising a device having a yielding bearing surface, means for introducing air under pressure to said device, means for delivering cloth to and from said device, and means for batting the pile of the 120 cloth so delivered.

11. An apparatus for erecting the pile in pile piece goods comprising pneumatic cushions, supports for said cushions, means for stretching the piece of pile fabric and 125 holding it taut over said cushions, and means for maintaining said cushions under air pressure.

12. An apparatus for erecting the pile in pile piece goods comprising a frame, devices 130

having resilient surfaces mounted on said frame, means for stretching the piece of pile fabric and holding it taut between said devices, said devices having plates with end pieces and a covering of impervious material secured thereto to form a closed chamber, and means for introducing a fluid under pressure to said chamber.

13. An apparatus for erecting the pile in
10 pile piece goods comprising a frame, two rotatable rollers mounted on said frame toward the ends of the same, two resiliently faced devices mounted on said frame between said rollers, retaining pins on the peripheries of said rollers, a ratchet wheel connected to each of said rollers, a pawl

in comparative relation to each of said wheels, and handles for operating said rollers.

In testimony whereof we have hereunto 20 signed our names in the presence of the subscribing witnesses.
